UNITED STATES PATENT OFFICE.

THOMAS L. BARKER, OF PHILADELPHIA, PENNSYLVANIA, ASSIGNOR TO PHILADELPHIA STEAM HEATING COMPANY, OF PHILADELPHIA, PENNSYLVANIA, A CORPORATION OF PENNSYLVANIA.

AUTOMATIC THERMOREGULATOR FOR BOILER AND OTHER FURNACES.

Application filed July 11, 1922. Serial No. 574,314.

To all whom it may concern:

Be it known that I, THOMAS L. BARKER, a citizen of the United States, residing in the city and county of Philadelphia, State of Pennsylvania, have invented a new and useful Automatic Thermoregulator for Boiler and Other Furnaces, of which the following is a specification.

My invention consists of a novel construction of a casing for a magnetic switch, said casing having upright end members in which the ends of the core of the solenoid magnets is supported, said upright ends also supporting parallel rods upon which are mounted suitable insulated stationary contacts and a movable contact also insulated from but slideable upon said rods, said movable contact being actuated in either direction according to requirements simultaneously with the oscillation of a switch lever of novel construction, which is actuated by the movement of the armature of said magnets, when the latter are energized.

It further consists of a novel construction of a magnetic switch having a hollow tube upon which the solenoid magnets are wound, said tube being slotted at points intermediate the inner juxtaposed ends of said magnets and the armature of said tube having a pin passing transversely therethrough and through said slots and being in engagement with the upper end of an oscillatory switch lever, whereby the ends of said transverse pin are adapted to actuate in the desired direction a movable contact mounted on guide rods carried by the ends of the switch casing.

It further consists in the novel manner of mounting and assembling the solenoid magnets, the rigid or stationary contacts and the movable contact coating therewith.

It further consists of other novel features of construction, as will be hereinafter fully set forth.

For the purpose of illustrating my invention, I have shown in the accompanying drawings certain forms thereof which are at present preferred by me, since the same will give in practice satisfactory and reliable results. It is to be understood, however, that the various instrumentalities of which my invention consists can be variously arranged and organized, and that my inven-

tion is not limited to the precise arrangement and organization of these instrumentalities as herein shown and described. 55

Figure 1 represents a plan view of the magnetic switch member of an automatic thermoregulator for a boiler or other furnace, embodying my invention. 60

Figure 2 represents a section on line 2-2 of Figure 1.

Figure 3 represents a section on line 3-3 of Figure 2.

Figure 4 represents a perspective view of 65 the guide rods, the insulating blocks movable thereon, the movable contact carried by said blocks, and the pendant arms depending from opposite ends of said blocks.

Similar numerals of reference indicate 70 corresponding parts.

Referring to the drawings:

In carrying out my invention, I employ a novel construction of magnetic switch 1, the detailed construction of said switch being as follows: 75

The solenoid magnets 7 and 8 are wound on a brass tube or core 9, whose ends are secured in the upright ends 10 of the base member 11 of the switch casing, which is composed of thin sheet metal. Above the magnets 7 and 8 are located the parallel brass or other rods 12, whose ends are also mounted in the upright end supports 10 and support the insulating block 13 at the left 80 of the apparatus, which is held in position by the screw 14, said block having the stationary or rigid contact 15 secured thereto by the screws 16 and 17. A similar insulating block 18 is secured to the rods 12, at 85 the right of the apparatus by the screw 19; and upon said block is secured the right-hand stationary or rigid contact 20, by means of the screws 21 and 22. It will be apparent that the rods 12 serve both as 90 supports for the pair of stationary contacts and the movable contact and also to brace and tie together the upright ends 10, so that a rigid and durable structure is produced. The core 9 also assists to tie the 100 upright ends 10 together, as is evident.

23 designates a steel plunger or armature, which has a pin 24 passing transversely therethrough, said pin being guided in the oppositely located slots 25 in the tube or 105 core 9. The ends of the pin 24 are engaged

by the hooks 26 located on each side of the tube 9, said hooks being carried by the lever 27, which is an element of the standard toggle switch 28, which need not be described in detail, as it forms per se no part of my invention, said switch being preferably a Hart and Hageman switch, No. 3721, as used in buildings to control lighting circuits, motors and the like, and being rated at 5 amperes, 250 volts, 10 amperes, 125 volts.

The transverse pin 24 at one of its extreme positions engages and actuates the pendant arm 29, which is secured to insulating block 30, which is freely movable on the rods 12 and has secured to its top, one end of the movable contact 31, the other end of said contact being secured to the right hand insulating block 32, which is also freely movable on said rods 12 and carries the pendant arm 33, which is engaged and actuated by the pin 24 when the latter moves to the right of the position seen in Figure 2.

It will be seen particularly in Figure 4, that the blocks 30 and 32, the contact 31 and the pendant arms 29 and 33 move as a unit, whenever one of said arms is hit by the pin 24, when the latter and the armature move towards or assume either of their extreme positions, which is effected by the energization of either of the magnets 7 or 8.

I preferably locate the pendant arms on opposite sides of the insulating blocks 30 and 32, as seen in Figure 4, but this arrangement may of course be varied, if desired.

It will now be apparent that I have devised a novel and useful automatic thermo-regulator for boiler and other furnaces, which embodies the features of advantage enumerated as desirable in the statement of the invention and the above description, and while I have in the present instance shown and described preferred embodiments thereof which will give in practice satisfactory and reliable results it is to be understood that the same is susceptible of modification in various particulars without departing from the spirit or scope of the invention or sacrificing any of its advantages.

Having thus described my invention, what

I claim as new and desire to secure by Letters Patent, is:—

1. In a device of the character stated, a magnetic switch composed of a base and upright ends, a hollow tube having its terminals seated in said ends, solenoid magnets wound on the outer ends of said tube, rods above said magnets having their outer terminals secured in said upright ends, stationary contacts mounted on and insulated from the outer portions of said rods, insulated blocks slidable on said rods intermediate said stationary contacts, a movable contact carried by said blocks, arms depending from said blocks, said blocks, contact and pendant arms moving as a unit, an armature in said tube, a transverse pin in said armature projecting through slots in said tube, and a switch lever engaging said pin, the latter being adapted to contact with and actuate said pendant arms and moving contact when said armature is attracted to either of its extreme positions by the energizing of either of said magnets.

2. In a device of the character stated, a magnetic switch comprising a base and upright ends, an elongated hollow tube having its terminals seated in said upright ends, solenoid magnets wound on the outer ends of said tube, a pair of spaced rods above said magnets having their outer terminals secured in said upright ends, a stationary contact mounted on and insulated from said rods and arranged above each magnet, insulated, spaced, blocks slidable on said rods intermediate said magnets, a contact plate fixed upon said blocks, oppositely disposed arms depending from said blocks, said blocks, contact and pendant arms moving as a unit, a slotted armature in said tube, a transverse pin in said armature projecting through said slotted part, and a pivotal switch lever engaging said pin, the latter being adapted to contact with and actuate said pendant arms and moving contact when said armature is attracted to either of its extreme positions by the energizing of either of said magnets.

THOMAS L. BARKER.
